UNITED STATES PATENT OFFICE

106,080

DESIGN FOR A SUN JACKET

Edward Baruch, New York, N. Y.

Application May 3, 1937, Serial No. 69,128

Term of patent 3½ years

To all whom it may concern:

Be it known that I, Edward Baruch, a citizen of the United States of America, residing in Manhattan, county of New York and State of New York, have invented a new, original, and ornamental Design for a Sun Jacket, of which the following is a specification, reference being had to the accompanying drawing, forming part thereof, wherein,

Figure 3 is a rear view of the sun jacket shown in Figures 1 and 2 showing the collar portion thereof in an upturned position to illustrate the entire rear of the sun jacket, as shown.

The instant garment comprises a backless middy type garment having a relatively wide front waist-band which forms a sash tie in the back, and having a sailor collar, short sleeves and shoulder flaps, all as shown.

I claim:

The ornamental design for a sun jacket, substantially as shown, and described.

EDWARD BARUCH.
